UNITED STATES PATENT OFFICE.

HENRY PHELPS GAGE AND EMILIO PASCUCCI, OF CORNING, NEW YORK, ASSIGNEES TO CORNING GLASS WORKS, A CORPORATION OF NEW YORK.

DESIGN FOR A HEADLIGHT COVER-GLASS.

52,436.

Specification for Design.

Patented Sept. 17, 1918.

Application filed October 18, 1917. Serial No. 197,343. Term of patent 14 years.

To all whom it may concern:

Be it known that we, HENRY PHELPS GAGE and EMILIO PASCUCCI, citizens of the United States, residing at Corning, in the county of Steuben and State of New York, have invented a new and original ornamental Design for Headlight Cover-Glasses, of which the following is a specification, reference being had to the accompanying drawing, forming part thereof.

The figure is a front view of an automo-

bile headlight cover glass having our design applied thereto.

We claim:

The ornamental design for a headlight cover glass as shown.

HENRY PHELPS GAGE.
EMILIO PASCUCCI.

Witnesses:

WILLIAM CHURCHILL,
ANNA MARGARET HAAR.
